H. A. BERQUIST.
RAILWAY TIE AND RAIL FASTENER.
APPLICATION FILED MAR. 4, 1914.

Patented July 7, 1914.

UNITED STATES PATENT OFFICE.

HENRY A. BERQUIST, OF ST. CROIX FALLS, WISCONSIN.

RAILWAY-TIE AND RAIL-FASTENER.

1,102,857.

Specification of Letters Patent.

Patented July 7, 1914.

Application filed March 4, 1914. Serial No. 928,300.

To all whom it may concern:

Be it known that I, HENRY A. BERQUIST, a citizen of the United States, and a resident of St. Croix Falls, in the county of Polk and State of Wisconsin, have invented a new and Improved Railway-Tie and Rail-Fastener, of which the following is a full, clear, and exact description.

Objects of my invention are to provide an efficient rail fastening means involving simple elements that will not be liable to become loose as are rail spikes of the usual form; to provide a rail fastening means that may be quickly and conveniently applied to the rails and ties, and as readily removed when required, and to provide a fastening means having the required strength to withstand the strains of use, while at the same time involving a minimum cost.

20 The invention resides in novel rail-engaging devices, and co-acting elements associated with the railway ties for retaining the said rail-engaging devices.

25 The invention will be particularly explained in the specific description following.

Reference is to be had to the accompanying drawings forming a part of this specification, in which similar characters of reference indicate corresponding parts in all 30 the views.

Figure 1 is a plan view showing the invention applied to a tie and rails; Fig. 2 is a side view with parts in transverse vertical section; Fig. 3 is a detail view, partly in section and partly in elevation, the view being taken at right angles to Fig. 2, and showing a slight modification in the rail-engaging devices; Fig. 4 is a perspective view of one of the clamps to retain the rail-engaging devices; Fig. 5 is a perspective view of one of the rail-engaging devices; and Fig. 6 is a view similar to Fig. 5, but showing a slight modification.

The invention is more particularly intended for use in connection with a metallic railway tie 10, U-shaped or channeled in cross section. Wood blocks 11 are received in the tie 10, and on said blocks the rails 12 seat. The fastening means for the rails include rail-engaging elements comprising heads 14 which overlie the rail flanges and shanks 13. The shanks 13 taper upwardly in the direction of the heads 14, the taper being preferably produced by a gradual increase of width of the shank in a direction laterally to the direction of the heads 14,

thereby presenting a beveled edge 13^a; thus the gradual lateral enlargement of the shank is in a direction at an angle normal to the inwardly extending heads 14. The inner 60 side or edge 13^b opposite the beveled edge 13^a, is perpendicular to the rail so as to lie flat against a side face of the tie 10, the result being that one face of the shank will lie against and be parallel with the side of the 65 tie, while the opposite outer edge is beveled to taper in an upward direction toward the head 14.

In connection with the shank 13 of the rail-engaging device, clamps 15 for retaining the shanks are provided, in the form of plates adapted to lie against opposite sides of the tie 10, bolt holes 16 being provided to receive transverse bolts 17 having nuts 18. The bolts 17 extend through the opposite 75 clamps 15, and through the sides of the tie 10 at opposite ends of the blocks 11, so that the said blocks are held between each pair of bolts 17 without the latter extending through the blocks.

80 The rail fastening devices are employed in pairs at each side of a rail, and a single clamp plate 15 engages an adjacent pair of the rail-engaging devices. As best seen in Fig. 4, the clamp plates have three-sided 85 sockets 15^a, open at top and bottom and at the inner sides. The outer wall 15^b of each socket 15^a is beveled so that the sockets taper in an upward direction and flare downwardly to correspond with the tapered form 90 of the shanks 13.

95 By the described construction it will be clear that any upward pull of the rail 12 due to the passing of a train will be resisted by the heads 14 of the rail-engaging devices, and the tapered form of the shanks 13 and sockets 15^a will effectively prevent the upward movement or loosening of the rail-engaging devices.

100 It will be readily understood that by the described construction, the fastening means may be quickly secured in place, and that to remove the same it will be only necessary to remove the bolts 17.

105 In Figs. 2 and 5, the beveled edge 13^a extends continuously from the lower end of the shank 13 to the head 14. In the form shown in Fig. 6, and also in Fig. 3, the rail-fastening device has a head 14^a corresponding with the head 14, a shank 13^a, a 110 perpendicular inner edge 13^b and an opposite outer beveled side edge 13^a. The said

beveled edge in the form shown in Fig. 6, terminates short of the head 14^a, there being a non-beveled or perpendicular portion 13^c above the bevel and between the same 5 and the head, the portion 13^c being of a height corresponding to the thickness of the rail flange. The construction in Fig. 6 is designed to give an ample thickness of material, and therefore ample strength to 10 the shank adjacent to the head 14^a, while at the same time providing the necessary beveled edge to be engaged by the corresponding bevel of the socket 15^a.

Having thus described my invention, I 15 claim as new, and desire to secure by Letters Patent:

1. In rail-fastening means, rail-engaging devices having heads and shanks that taper upwardly toward the heads; and clamps securable to a tie at the sides thereof, said clamps having three-sided sockets presenting openings at top and bottom and at the inner side to receive the said tapered shanks, 25 the said sockets tapering upwardly to conform to the shape of the shanks.

2. The combination with a channel tie, of blocks therein to sustain railway rails, rail-engaging devices comprising heads and ta-

pered shanks, clamps attachable to opposite sides of the tie and formed with tapered 30 sockets to receive the said tapered shanks, and transverse bolts passing through the said clamps and transversely through the tie at opposite sides of the said blocks.

3. In rail-fastening means, rail-engaging 35 devices comprising heads and shanks tapered in an upward direction, and clamps securable to the tie and formed with sockets to engage the said tapered shanks.

4. In rail-fastening means, rail-engaging 40 devices comprising heads and shanks, the said shanks having inner perpendicular edges and outer beveled edges, the perpendicular edges being adapted to lie flat against the sides of a tie, and clamps securable to the tie and having sockets presenting outer walls tapered to correspond with the beveled edges of the said shanks.

In testimony whereof I have signed my name to this specification in the presence of two subscribing witnesses.

HENRY A. BERQUIST.
